BASSINET OR SIMILAR ARTICLE

Harold L. Kirby, Glendale, Calif.

Application June 8, 1950, Serial No. 10,409

Term of patent 14 years

(Cl. D5—4)

To all whom it may concern:

Be it known that I, Harold L. Kirby, a citizen of the United States, residing at Glendale, State of California, have invented a new, original, and ornamental Design for a Bassinet or Similar Article, of which the following is a specification, reference being had to the accompanying drawing, forming a part hereof.

Fig. 1 is a perspective view from above one corner of the bassinet or similar article, showing my new design.

Fig. 2 is an elevational view of the backside of the bassinet or similar article shown in Fig. 1.

Fig. 3 is an elevational view of the end of the bassinet or similar article not shown in Fig. 1.

I claim:

The ornamental design for a bassinet or similar article, as shown.

HAROLD L. KIRBY.
